(57) **CLAIM**

The ornamental design for a bottle, as shown and described.

DESCRIPTION

FIG. 1 is a top front perspective view of a bottle, showing my new design;

FIG. 2 is a bottom front perspective view thereof;

FIG. 3 is a top back perspective view thereof;

FIG. 4 is a bottom back perspective view thereof;

FIG. 5 is a front elevation view thereof;

FIG. 6 is a back elevation view thereof;

FIG. 7 is a left side elevation view thereof;

FIG. 8 is a right side elevation view thereof;

FIG. 9 is a top view thereof; and,

FIG. 10 is a bottom view thereof.

The broken lines shown in the figures illustrate portions of the bottle that form no part of the claimed design.

1 Claim, 9 Drawing Sheets
